Primary Examiner—Bernard Ansher*Assistant Examiner*—Prabhakar Deshmukh*Attorney, Agent, or Firm*—Gottlieb, Rackman & Reisman[57] **CLAIM**

The ornamental design for the storage receptacle, as shown and described.

DESCRIPTION

FIG. 1 is a perspective view of a storage receptacle showing my new design;

FIG. 2 is a top plan view thereof;

FIG. 3 is a front elevational view thereof;

FIG. 4 is a side elevational view thereof;

FIG. 5 is a rear elevational view thereof; and,

FIG. 6 is a bottom plan view thereof.

The dash lines are intended to represent fold lines. The broken line showing of cards is for illustrative purpose only and forms no part of the claim.
